Patented Nov. 11, 1969

215,935

DIRECTIONAL CONTROL VALVE

Jerald H. Gens, Minnetonka, Minn., assignor to Char-Lynn Company, Eden Prairie, Minn., a corporation of Minnesota

Filed Aug. 29, 1968, Ser. No. 13,322

Term of patent 14 years

Int. Cl. D23—01

U.S. Cl. D23—19

FIG 1

FIG 2

FIG 3

FIG 4

FIG 5

FIG 6

FIG. 1 is a perspective view of a directional control valve embodying my new design;

FIG. 2 is a front elevational view thereof;

FIG. 3 is a side elevational view thereof;

FIG. 4 is a top plan view thereof;

FIG. 5 is a rear elevational view thereof; and

FIG. 6 is a bottom plan view thereof.

I claim:

The ornamental design for a directional control valve, substantially as shown.
